UNITED STATES PATENT OFFICE.

CHARLES E. CHAPMAN, OF FORT EDWARD, NEW YORK, ASSIGNOR OF ONE-HALF TO
JOSEPH GOODFELLOW, OF FORT EDWARD, NEW YORK.

HEATER.

Application filed March 23, 1920, Serial No. 368,191. Renewed April 5, 1924.

To all whom it may concern:

Be it known that I, CHARLES E. CHAPMAN, a citizen of the United States, residing at Fort Edward, in the county of Washington 5 and State of New York, have invented certain new and useful Improvements in Heaters, of which the following is a specification.

This invention relates to a heater adapted for attachment to internal combustion engines for the purpose of utilizing the exhaust heat from the engine to vaporize the liquid particles in the fuel mixture from the carburetor and thus prevent condensation within the inlet manifold of the engine, 10 while at the same time permitting the use of the present day lower grades of fuel oils without deleterious dilution of the crank case lubricant.

In detail, the invention consists of a unit 20 heater feeding the inlet manifold from the carburetor through a group of flues or tubes around which the exhaust gases from the engine are circulated.

The invention has, as another object, the 25 provision of a heater which is so arranged and constructed that a flame may be produced therein for the purpose of initially heating the heater to provide for easy starting of an internal combustion engine in cold 30 weather.

In the drawings:

Figure 1 is a side elevation of the heater. 35 Figure 2 is a vertical section of the same, Figure 3 is a section on the line 3—3 of

Figure 1, Figure 4 is a section on the line 4—4 of Figure 1,

Figure 5 is a perspective view of the deflector plate.

The invention, as herein shown, is combined with the inlet manifold 1 and the exhaust manifold 2. The inlet manifold is provided with an opening 3 having a flange 4 against which a flange 5 of the heater abuts 40 and which flanges are held together by suitable bolts 6. The flange 5 is joined with a

passage 7 which enters a rectangular chamber 8 having a suitable heat insulating cover 9 and which is confined between a top plate 10 and a header plate 11 by means of bolts 12, said bolts also extending through a flange 13 on the body 14 of the heater. The head plate 11 receives one end of a group of tubes 55 15, the other ends being received in a bottom plate 16 which forms the upper wall of

the chamber 17 having the asbestos or other heat insulating cover 18 and which chamber 17 is held in place by suitable bolts 19 and nuts 20, as indicated. The chamber 17 is provided with an inlet flange 21 for bolting 60 to the carburetor. Secured to the forward side of the heater chamber 14 is a vertical riser 22 having an opening at 23 into the heater chamber and said riser is held in place by a strap 24 secured by a bolt 25 in 65 any suitable manner. The upper end of the riser 22 connects by means of a flexible tube 26 with the exhaust manifold 2, as shown. Within the heater chamber 14 and at one side, as clearly shown in Figure 4, is the angularly disposed deflector plate 27 having the opening 28 which is staggered with respect to an opening 29 connecting with an exhaust flue 30 attached to the exhaust outlet 31 secured in place by suitable fastening 70 means 32.

Within the heater chamber 14 and disposed around the tubes 15 at the bottom thereof is some loose asbestos filling, as indicated at 33, which, on initial starting of the 80 engine, may be saturated with gasoline or the like and ignited for the purpose of heating the heater tubes to provide for easy starting in connection with priming of the engine directly in the cylinder.

In the operation of the heater the carburetted air is received within the chamber 17 and passes upwardly through the heater tubes 15, into the chamber 8 and out into the inlet manifold 1. When the 90 engine is functioning the exhaust gases pass from the flexible tube 26, down through the riser 22, through the opening 23 into the heater chamber 14, around the tubes therein heating the same to a high degree and finally passing out the opening 28 in the deflector 29 and down through the exhaust flue 30. It will be seen that the course pursued by the incoming carburetted air is through a highly heated group of 95 tubes.

It is to be understood that in carrying the invention into practice the heater may be combined with any of the present day type of carburetors and internal combustion engines as an attachment therefor and will increase the efficiency of such devices very materially.

Attention is now directed to the fact that, 105 as particularly shown in Figure 4, the rear 110

side wall and one end wall of the body of the heater are integral and, as brought out in Figures 2 and 3, are permanently connected to the plates 11 and 16 at the ends of the chamber. Similarly, the front wall of the heater body and the other end wall thereof are integral. However, the front wall and said end wall instead of being permanently secured in place, are detachably held in position, mating with the permanently mounted walls of the body, by the strap 24. Accordingly, by loosening the bolt 25 to release the strap 24, the front wall of the heater body and the end wall integral with said front wall may be displaced as a unit for exposing the tubes 15. Thus, free access to said tubes throughout the length thereof may be had for cleaning the tubes of soot or other incrustation thereon deposited by the exhaust gases flowing around the tubes. As will be perceived, the device may thus be maintained to function with maximum efficiency.

I claim:

25. 1. In a fuel charge heater for internal

combustion engines, spaced plates, a group of charge conducting tubes extending between said plates secured thereto, an exhaust gas chamber housing the tubes and including an integrally formed back wall 30 and end wall permanently secured to the plates and a removable front wall and integral opposite end wall mating with said first mentioned walls, and a strap surrounding the chamber removably securing the front 35 wall and the latter end wall in position whereby the front wall and latter end wall may be displaced for cleaning the tubes.

2. In a fuel charge heater for internal combustion engines, a group of charge conducting tubes, an exhaust gas chamber housing the tubes and formed of companion sections one permanently mounted and the other removable for cleaning the tubes, and fastening means encircling the chamber removably securing the latter section to mate with said first mentioned section.

In testimony whereof I affix my signature.

CHARLES E. CHAPMAN. [L.S.]
